UNITED STATES PATENT OFFICE.

EDWARD COTTY, OF WASHINGTON, DISTRICT OF COLUMBIA.

IMPROVEMENT IN ARTIFICIAL ARMS.

Specification forming part of Letters Patent No. 40,397, dated October 27, 1863.

To all whom it may concern:

Be it known that I, EDWARD COTTY, of Washington city, in the District of Columbia, have invented a new and useful Improvement in Artificial Arms; and I hereby declare that the following is a full and exact description thereof, reference being had to the accompanying drawings, and to the letters of reference marked thereon.

The nature of my invention consists, first, in constructing the whole mechanism of my arm of metal, avoiding the use of catgut, whalebone, wood, or any other organic substance; secondly, in the construction of the elbow-joint, whereby the position of the forearm and stump can be varied, and by this variation the fingers may be shut and opened; thirdly, in the peculiar construction of that part representing the wrist of the natural hand, which allows the hand to be turned to about the extent of the natural one; fourthly, in the arrangement and construction of the mechanism which moves the fingers, avoiding the use of ratchet-wheels, springs, pawls, &c.; fifthly, in the application of a peculiarly-shaped fork-holder.

In the annexed drawings, making a part of this specification, Figures 1, 2, and 3 are perspective views of the artificial arm when the hand is opened and the arm stretched, showing the same from front, side, and rear. Figs. 4 and 5 are perspective views of the artificial arm when the hand is shut and the arm bent, showing the same from front and rear. Fig. 6 is a perspective view of the artificial arm, showing its leather covering and the straps by which it will be fastened to the stump, arm, and shoulder. Figs. 7 and 8 represent my "elbow-joint," the imitation of the articulation of the "ulna" and "radius," with the "humerus" in two different positions. Figs. 9 and 10 illustrate the operation of the guide and spiral spring assisting in opening and shutting the fingers. Fig. 11 shows the shape and construction of the lower guide plate or disk of my wrist. Fig. 12 is a top view. Fig. 13 is a side view; and Fig. 14 is a section through the upper guide or lower portion of my hand, being the second part of my joint of the wrist, the imitation of the articulation of the forearm with the "carpus." Figs. 15 and 16 are to explain the operation of my imitation of the metacarpal bones, the first and second pha-

langes and the muscles of the hand, fingers and thumb included.

Similar letters of reference in each of the several figures indicate corresponding parts.

To enable others skilled in the art to make and use my invention, I will proceed to describe its construction and operation.

The curved guards 1 2 3 are covered by a socket, A, formed of leather, into the shape of a stump or arm to which the same is to be applied. This socket is provided with straps and buckles, as usual, for attaching the same into place. *a a* are two metallic straps from said stump or arm to the elbow-joint *b b*, connected by the guards 1, 2, and 3. The bones of the forearm, the ulna and radius, are represented by the two metallic straps *c c*, connecting the elbow-joint with the hand, being fastened to the ring *d*, surrounding and holding the lower portion, *e*, of the hand *f*, as shown in Figs. 15 and 16. By this arrangement the hand *f* will be allowed to be turned around its axis, guided by the ring *d*. The lower portion, *e*, of the hand *f* (shown in Figs. 12, 13, and 14) is provided with two projecting pins, *g g*, passing through corresponding holes, *h h*, in disk *i*. (Represented in Fig. 11.) Guards 4 and 5 and a stationary cross-piece, *k*, connect and hold in a firm position the two straps *c c*, the cross-piece *k* serving as rest for the spiral spring *l* around the bolt or pin *m*, and thereby assisting the bending and stretching of the arm, and making these movements more elastic. At the elbow-joint the double-armed bent levers *n n* (shown in Figs. 7 and 8, and in the perspective views) are attached to the metallic straps *a a*, for the purpose to attach and give motion to the rods *o o*, which are connected with the cross-pieces *p* and *q*, the cross-piece *p* being provided with a circular hole, *r*, for the passage of pin or bolt *m*, and cross-piece *q* is provided with two pins, *u u*, working in the curved guide-holes *v v* of disk *i*, and connects this disk with the rods *o o*. Both cross-pieces *p* and *q* are sliding in the perforations *s s t t* of the metallic straps *c c*. It will be easily perceived that by bending the arm—viz., by inclining the straps *c c* toward the straps *a a*—the rods *o o* will move forward, the cross pieces *p* and *q* sliding in perforations *s s t t*, and the disk *i* sliding on the two pins *g g* of the lower portion, *e*, of the hand, as illustrated by figures. To disk *i* are

fastened by screws and nuts, or in any other adjustable manner, five rods, *w w*, passing the opening of lower portion, *e*, being inclosed by a metallic casing, *f'*, representing the middle hand, (metacarpus,) and secured at their upper ends to short single-armed levers *x x*, Fig. 16, four of which levers, transmitting motion to the four fingers, turn around a common axis, *y*, Figs. 3 and 15. The other lever, transmitting motion to the thumb, turns around another axis, *z*, Figs. 3 and 15, the latter having an inclined position to the former axis. By this arrangement, resembling that of the carpal bones of the natural hand, the most important motion—that which brings the thumb in apposition to the fingers, and enables to grasp—is most successfully imitated. The first or metacarpal phalanges are represented by a row of five rods, *d d*, of different lengths, being connected at their lower or metacarpal ends with the levers *x x*, Fig. 16, and at the upper ends with the similar levers, *B B*, each swinging around an axis supported by and fastened to the hollow metallic tubes *j j*, Figs. 1, 2, 3, and 16, inclosing the rods *d d*. These tubes *j j* are attached to the metallic casing *f'* by the axes *y* and *z*, and may turn around them. The third or unguinal phalanges are represented by another row of five rods, *d d*, of proportional length, being at their lower end connected with the levers *B B*, and at their upper extremities fastened to the hollow metallic parts *e e*, representing the terminations of the fingers, by pins *u u*. It will be seen that one row of rods, representing the second or middle phalanges, have been left out to simplify the construction, but it can easily be added, if required.

The operation at this part of my arm, respectively of the hand and fingers, including the thumb, may, according to the above description, easily be understood. By bending the arm, rods *o o* will move forward the disk *i*, as described hereinbefore, and this disk drives forward the rods *w w x x d d* turning the small levers to which they are attached around their respective centers of motion, and pulling thereby the fingers toward the palm of the hand and the thumb toward the forefinger or index, whereby any article may be pressed therein and between them, so as to hold the same firmly, according to the will of the operator, by bending the arm more or less. Consequently, by stretching the arm more or less, the fingers are more or less straightened. The fork-holder *w*, consisting of

four elastic laps, 1, 2, 3, and 4, and a bottom screw, 5, (shown in Fig. 17,) may be screwed into the palm of the hand *f* at any proper place, *a*, Fig. 1, and is constructed in such a way that the handle of any fork in common use may be put into and firmly held by the elastic laps 1, 2, 3, and 4, Fig. 17.

The advantages of my invention are as follows: First, a close imitation of the actual movements of a sound human arm, therefore great comfort and utility; secondly, great simplicity and substantiality, therefore cheapness; thirdly, a minimum of friction and the absence of ratchet-wheels and pawls, therefore of wear and noise; fourthly, the absence of hygroscopic materials in the construction of my arm, therefore of extraordinary shrinkage.

I do not claim the construction of an artificial arm, nor do I confine myself to the peculiar shape of rods *o o*, bent lever *n n*, or of ring *d* and lower portion, *e*, of hand *f*, as this may be changed without abolishing the principle of my construction; but

What I claim as new and of my invention, and desire to secure by Letters Patent, is—

1. The elbow-joint *b b*, when constructed substantially as described hereinbefore, with the rods *o o* and slides *s s t t*.

2. The ring *d*, fastened to the straps *e e*, surrounding and holding the lower portion, *e*, of hand *f*, and allowing the latter to be turned around its axis, as specified above.

3. The spring *l* around pin *m*, in combination with cross-piece *k* and disk *i*, assisting the bending and stretching of the arm, constructed and arranged as described hereinbefore.

4. The disk *i*, with the two curved guide-holes *v v*, for the reception of pins *u u*, forming the bottom plate of rods *w w w*, being constructed and arranged as shown in the several figures, and as described above.

5. The rods *w w*, moving the levers *x x* on the inclined axes *y* and *z*, being adjustable on the bottom plate or disk, *i*, as described within, in combination with rods *x x d d* and levers *B B*, arranged as specified, and for the purpose set forth.

6. The construction of my fork-holder *w*, consisting of four elastic laps 1, 2, 3, and 4, and the screw 5, for the purpose specified hereinbefore.

EDWARD COTTY.
